UNITED STATES PATENT OFFICE.

GEORGE SWEANOR, OF MONTREAL, QUEBEC, CANADA, ASSIGNOR OF ONE-HALF TO EDWARD WILLIAM BEUTHNER, OF SAME PLACE.

AMMONIA-ENGINE.

SPECIFICATION forming part of Letters Patent No. 284,987, dated September 11, 1883.

Application filed June 4, 1883. (No model.)

To all whom it may concern:

Be it known that I, GEORGE SWEANOR, of the city of Montreal, in the District of Montreal and Province of Quebec, Canada, have 5 invented certain new and useful Improvements in Ammonia-Engines; and I do hereby declare that the following is a full, clear, and exact description of the same.

My invention relates to that class of engines in which the gas or vapor generated from ammonia or other liquid of low boiling-point is substituted for steam as the motive force; and it consists in means by which I secure the perfect liquefaction of the gas and its return in 10 liquid form to the boiler. It is adapted for use in connection with all classes of engines, as in no case is any alteration of the main features of construction required, and may be thus described: The boiler, which may be of any 15 desired kind, is charged with liquid ammonia, and the gas generated from this by heat is taken to the cylinder in the usual way, works the piston, and passes off by the exhaust. In addition to these ordinary features 20 of construction I place in any suitable position relatively to the boiler and engine a vessel or reservoir containing liquid ammonia of the same strength as that in the boiler, which is kept cool by the circulation of water. 25 This vessel I call the "absorber," and from it is taken a feed or supply pipe connected with the boiler, into which a pump worked by the piston cross-head or in any other suitable manner forces the liquid in the usual way. 30 The gas, which, in passing off from the exhaust, holds a proportion of steam, is taken to a vessel which I call the "cooler," and is there reduced in temperature by contact with surfaces cooled by the circulation of water. It 35 is then taken off by a pipe from the cooler to the absorber, and met on its way by a column of liquid ammonia drawn from the absorber and forced into the pipe by a pump, by which 40 it is reliquefied and passes along the downwardly-inclined pipe to the absorber, which is thus always kept replenished with liquid ammonia.

For full comprehension of my invention reference must be had to the annexed drawings, in which Figure 1 is a plan view of a

horizontal stationary engine constructed upon my plan to use ammonia or like liquid. Fig. 2 is an end view of same; Fig. 3, a sectional view on line $x-x$; Fig. 1; Fig. 4, a similar view on line $z-z$, Fig. 1; and Fig. 5, a detail, enlarged, 55 of stuffing-box.

Similar letters of reference indicate like parts.

It will be understood that the usual and well-known construction of a horizontal engine is only shown here sufficiently to insure the comprehension of the invention, and that parts of the mechanism which do not relate thereto may be omitted.

A is the boiler, A' the steam-drum, and a 60 the feed-pipe to the steam-chest B' of the cylinder B, with piston operating, as usual, main driving-shaft with fly-wheel and any means of transmitting motion, all these being of any usual construction, and therefore not material 70 to the invention.

C is the vessel or reservoir which I term the "absorber," made of some such size and proportion as that shown, and having internal perforated diaphragms, C', and pipes C², so as 75 to allow of the circulation through it of water to keep cool the liquid ammonia contained in the body of the vessel, which is provided with a gage, c.

D is the supply-pipe, provided with stop-cock D', leading from the absorber C to the pump E, which is of any ordinary type, placed where shown, and operated by the cross-head in the usual way. By this pump the liquid is forced by the pipe f into the feed-heater 85 F, and thence through the pipe G into the boiler. (The feed-heater may in many cases be omitted and the pipe G be simply a continuation of D.)

H is the exhaust-pipe taken from B' to the 90 vessel K, which I term the "cooler," the gas and steam held in suspense passing through pipes K', over surfaces cooled by the circulation of water, and carried off by the pipe L, communicating with the absorber C.

M is a pipe connecting the lower part of the ammonia-chamber in the absorber C with the pipe L, and having mounted on it a pump, M', in this case worked by the crank, by which 95 liquid ammonia is drawn off from the ab- 100

sorber and forced into the pipe L, there coming into contact with the gas from the cooler K and liquefying it, the gas thus liquefied falling down through the pipe L, which is set at any 5 desired angle of inclination, into the absorber C. The construction of the two vessels—the absorber C and cooler K—may be varied from that shown in the drawings—as, for instance, by substituting a coil or worm for the pipes 10 so long as a cooling-surface is presented in the latter to the gas passing through and in the former to the liquid contents of the vessel. As the absorber C is on a lower level than K, the water is by preference let first into the 15 cooler, through which it circulates, and then passes off by the pipe k to the absorber C, from which, after circulation, it is let off.

The operation of my invention resembles so closely that of an ordinary steam-engine that 20 it is sufficient to say that the boiler A and absorber C are both supplied with liquid ammonia of equal strength, and that the gas evolved therefrom in the boiler works the engine, and, passing from the exhaust to the cooler, is there 25 reduced in temperature, and on its passage through the pipe L to the absorber is liquefied by the contact therewith of liquid ammonia pumped up from the absorber through the pipe M, falling back, when so liquefied, in the 30 absorber, from which the expenditure of ammonia in the boiler is supplied, the pump D, when the stop D' is opened, acting in the usual way.

In order to prevent what has usually been 35 found the most serious defect in ammoniacal-gas engines—viz., the difficulty of preventing the escape of the volatile gas from the joints—a difficulty which has been but imperfectly remedied by the use of petroleum as packing—40 I use the construction shown particularly in Fig. 5, and now to be described. In this figure N is the stuffing-box; O, the gland, and P the packing, which may be of hemp or any substance in ordinary use for the purpose. 45 The stuffing-box is, however, formed with a gas-chamber, N', from which a pipe, Q, communicates with the exhaust H, thus drawing off any gas entering the chamber N', which might otherwise escape through the packing. 50 This arrangement of stuffing-box is applied to the piston and pump rods, and in all cases in which lubricated packing-joints exist, and, as shown in Fig. 1, these pipes Q may be so ar-

ranged as to have but one junction with the main exhaust H. I propose, in addition to 55 these auxiliary exhausts, to connect the safety-valve on the boiler with pipe H by a pipe, Q', so that an extra pressure of gas will, instead of being blown off, be taken to the cooler to be 60 liquefied, thus avoiding waste.

It must be clearly understood that although 65 my invention is in the present case shown and described as applied to one type of horizontal engines, it can be used equally well with all kinds of engines without altering their construction or the nature of the invention itself.

As brass and copper are affected by the ammonia liquid and gas, the valve-seats and stems, joints, junctions, &c., must be made of iron or white-metal.

I am aware that ammoniacal-gas engines have been in use before my invention; but in 70 most of these the condensation is effected by liquid drawn from the boiler and artificially cooled, thus accomplishing the purpose at the 75 cost of the energy generated in the boiler.

I am also aware that the gas from the exhaust of an ammonia-engine has been brought 80 into contact with a solution of ammonia drawn from a reservoir; but in one instance the result claimed is not the liquefaction of the gas, and in none does the reservoir serve to supply the boiler. I therefore disclaim all such methods and apparatus, what I do claim being 85 as follows:

1. The method of liquefying gas or vapor generated from ammonia or other liquid of low boiling-point, and used as the motive force in an engine by bringing it, after being cooled, in contact with a column of ammonia or like 90 fluid forced up from a separate reservoir, into which such gas falls when liquefied, all as herein set forth.

2. The combination, with an engine of any type in which liquid ammonia is substituted 95 for water, of a vessel through which the vapor from the exhaust passes and is cooled, and a reservoir or absorber into which the gas, when liquefied, falls and from which the boiler-supply is replenished, all as herein set forth.

Montreal, 26th day of May, A. D. 1883.

GEORGE SWEANOR.
